UNITED STATES PATENT OFFICE.

PAUL V. HUMPHRIES, OF QUINTON, OKLAHOMA.

INTERCHANGEABLE ANTERIOR TOOTH.

1,258,413.

Specification of Letters Patent.

Patented Mar. 5, 1918.

Application filed April 23, 1917. Serial No. 163,957.

To all whom it may concern:

Be it known that I, PAUL V. HUMPHRIES, a citizen of the United States, residing at Quinton, in the county of Pittsburg and 5 State of Oklahoma, have invented certain new and useful Improvements in Interchangeable Anterior Teeth; and I do declare the following to be a full, clear, and exact 10 description of the invention, such as will enable others skilled in the art to which it appertains to make and use the same.

My invention relates to improvements in artificial teeth, and its object is to provide an anterior artificial tooth of porcelain with 15 a metal backing possessing great strength, durability, and flexibility, and which will have an absolutely natural appearance and will not cause annoyance to the wearer.

Another object of my invention is to so 20 construct an artificial tooth of this character that none of the backing will be displayed, and which will be so disposed as to be perfectly sanitary and applicable to any case, long or short bite, or gum condition, and 25 which will be interchangeable.

Another object of my invention is to provide an artificial tooth of this character which is equally applicable as a crown, bridge-tooth or as a plate tooth using either 30 a metal or rubber base for the plate.

To this end my invention resides in the novel features of construction, combination, and arrangement of parts to be more fully 35 hereinafter described and claimed and taken in connection with the accompanying drawings which form a part of this application.

In the accompanying drawing:

Figure 1 is a side elevation of a tooth constructed in accordance with my invention;

Fig. 2 is a rear view of the same;

Fig. 3 is a vertical longitudinal section on the line 3—3 of Fig. 2;

Fig. 4 is a rear elevation of the tooth;

Fig. 5 is a longitudinal section on the line

45 5—5 of Fig. 4;

Fig. 6 is a top plan view of Fig. 5;

Fig. 7 is a rear view of two teeth in joined 50 relation;

Fig. 8 is a perspective view of the cap or 55 backing of the tooth; and

Fig. 9 is a longitudinal section showing the tooth as applied to a root.

Reference being had to the accompanying drawing, the numeral 1 indicates generally 55 an anterior tooth made of porcelain and which is provided with a reduced rear por-

tion 2 molded in the shape of a four-sided pentagon to form a base portion for the tooth and which has a flat top 3 and downwardly and outwardly beveled or inclined 60 side walls 4 and 5 and a similarly downwardly inclined and outwardly beveled rear wall 6. The side walls 4 and 5 are convergent from the front to the rear portion of the tooth and are provided at their front 65 edges with a pair of downwardly extending grooves 7 which are extended downwardly in the sides and at substantially right angles to the flat top 3 of the base portion. These grooves are disposed with their inner walls 70 in parallel relation to one another throughout their length for a purpose to be herein-after described. The depth of the grooves is the depth of inclination of the sides and the bottom of the grooves are disposed parallel 75 to the plane of the flat top 3.

In order to insure a strong durable construction, the flat top 3 of the base portion is set at substantially right angles to the line of the stress of mastication, and the 80 bevels of inclinations of the side or end walls of the base portions are at angles from 60° on the sides to 80° on the rear. On the front edge of the base portion and rising from the top thereof and extending outwardly to the 85 gingival margin of the tooth is formed an inclined surface 8 at an angle of practically 65° to form a shoulder at the front of the base portion of the tooth and extending upwardly to the gingival margin. 90

Disposed centrally in the flat top of the base portion 2 is an elongated socket 9 which extends downwardly into the tooth and is shaped to follow the contour of the front and rear walls of the tooth as clearly illustrated in Fig. 2. Owing to this construction, the socket will be tapered toward its lower end and will be given a slightly curved 95 formation.

The metal backing used in conjunction 100 with this artificial tooth may be made of any suitable heat-resisting material and it will be so disposed as not to be visible, and comprises a metal plate 10 having inclined side and end walls 11 and 12 respectively, the 105 angles of inclination of the walls being equal to the angles of inclination of the side and end walls of the base portion 2 of the tooth, whereby they may be engaged there-over to fit snugly thereto. The backing is 110 provided with a flat top to engage over the flat top of the base portion of the tooth and

at its interior or front edge is provided with an outwardly inclined flange 13 which is adapted to abut against the shoulder formed by the inclined surface 8 in the front side 5 of the tooth when the backing and tooth are engaged. Centrally located on the flat portion of the metal backing is a substantially hooked-shaped lug 14 which is adapted to extend downwardly into the socket provided 10 in the base portion of the tooth and to be engaged therein, and at the front ends of the side walls 11 of the backing are provided integrally formed inwardly extending flanges 15 arranged with their inner edges 15 in parallel relation throughout their length and adapted to be engaged in the grooves 4 formed in the inclined sides of the base portion.

Owing to the inner walls of the grooves 20 being in spaced parallel relation throughout their length and the construction of the inner edges of the flanges formed on the side walls of the backing it will be readily seen that the tooth may be applied to the backing 25 or the backing applied to the tooth without any resistance being offered by the engagement of the flanges with the grooves. These grooves and flanges when engaged will serve to prevent any rocking or twisting 30 of the tooth, thereby greatly strengthening the construction of the same. The grooves and socket are so arranged that a plane passing through the grooves will intersect a portion of the curve of the socket 35 9 formed in the base portion, and when the backing is applied, the lug 14 formed on the backing will be engaged in the recess in a substantially hooked manner, and owing to the arrangement of the grooves and the 40 socket as hereinbefore described, any twisting or lateral strain upon the tooth will be taken up and distributed evenly at all points throughout the tooth and backing so as not to bring undue stress upon any portion of 45 the tooth and thereby weaken the same.

The socket 9 is of sufficient size as to leave an equal thickness of the walls at the front and rear of the tooth, and owing to this construction, it will be seen that no undue strain 50 will be applied upon either of the walls of the tooth as they are of the same thickness throughout.

In the mounting of my improved artificial tooth, gold is burnished over the end of the 55 tooth root, which is cut as desired, and pierced for pin reception, the tooth and backing are then placed together, the tooth being selected as to color and size, the backing waxed in place, tooth removed and backing 60 invested for soldering, afterward, tooth is cemented into the backing and polishing is done as desired. For bridge work, the manner of mounting is similar except that suitable abutments are formed and the backings 65 mounted therebetween. It will be read-

ily seen that this construction entirely eliminates the necessity of the individual dentist manufacturing the backing which oftentimes will produce a misfit and cause considerable trouble and inconvenience to the 70 wearer.

All backings are manufactured and stamped to shape and molded to fit the bevels of the body portion of the teeth and all the bevels of the teeth in turn are preferably ground to fit the backings when the teeth are manufactured, and therefore all teeth will be interchangeable as the size of the backings and the base portions of the teeth are standardized regardless of the size 80 or location of the tooth.

I do not confine myself to the use of this backing for any special work such as crown work or bridge work, but I desire it to be understood that owing to its construction, 85 the backing may be applied in bridge work or suitably supported on a pin inserted in the root of a tooth for crown work, as desired.

In the accompanying drawing I have 90 illustrated my improved artificial tooth as applied as an anterior tooth, but it is to be understood that the same construction may be applied to other various forms of teeth. I desire it also to be understood that I do 95 not limit myself specifically to the materials and details of construction employed in this embodiment of my invention, but that such may be used as may fall within the scope of the appended claims.

I wish it also understood that the flanges and grooves on the metallic backing and body of the tooth respectively may be dispensed with if desired, and that the shape of the attaching lug may be varied, or that 105 the attaching lug may be made corrugated or of plain surface as desired, the corrugated form being the preferred embodiment of my invention.

I claim:

1. An artificial tooth as described having a reduced rear base portion, a beveled shoulder rising from the front edge of said base to the gingival margin of the tooth, said base having a flat top at a substantially 115 right angle to the stress of mastication, and having convergent downwardly and outwardly beveled side walls and a similarly beveled rear wall, said base having an elongated socket therein extending downwardly 120 into the tooth and following the contour of the front and rear walls of the tooth.

2. An artificial tooth as described having a reduced rear base portion, a beveled shoulder rising from the front edge of said base 125 to the gingival margin of said tooth, said base having a flat top substantially at right angles to the stress of mastication and having convergent downwardly and outwardly beveled side walls and a similarly beveled 130

rear wall, said base also having an elongated socket therein extending downwardly into the tooth and following the contour of the front and rear walls thereof, said base having grooves in the sides thereof at substantially right angles to the top and relatively parallel throughout their length.

3. An artificial tooth as described having a reduced rear base portion, a beveled shoulder rising from the front edge of said base to the gingival margin of the tooth, said base having a flat top at a substantially right angle to the stress of mastication and having convergent downwardly and outwardly beveled side walls and a similarly beveled rear wall, said base having an elongated socket therein extending downwardly into said tooth and following the contour of the front and rear walls thereof, and a 15 backing having a flat top, downwardly inclined sides, and rear end walls to conform to and engage over the said base portion, a flange at the front end of said backing to abut against the said shoulder, and a lug on 20 the backing to engage in said socket.

25 4. An artificial tooth having a base por-

tion provided with downwardly extending inclined side walls, a flat top, a shoulder rising therefrom at the front, said tooth having relatively narrow grooves extending downwardly in the side walls adjacent said shoulder, the depth of said grooves being the depth of inclination of the side walls with their inner walls parallel throughout their length the bottoms thereof being parallel to the plane of said flat top, said base portion being provided with an elongated socket in its top extending downwardly into the tooth and curved therein, the plane of the inner walls of the grooves intersecting a 40 portion of the curve of said socket and a backing to be received over said base portion provided with flanges to completely engage in said grooves, and a substantially hooked lug to engage in said socket.

45 In testimony whereof I have hereunto set my hand in the presence of two subscribing witnesses.

PAUL V. HUMPHRIES.
